UNITED STATES PATENT OFFICE.

GEORGE COATES, OF WINTERSLOW, ENGLAND.

FENCING-WIRE STRETCHER.

No. 831,982.

Specification of Letters Patent.

Patented Sept. 25, 1906.

Application filed August 18, 1905. Serial No. 274,706.

To all whom it may concern:

Be it known that I, GEORGE COATES, a British subject, residing at Winterslow, in the county of Wilts, England, have invented 5 a new and useful Fencing-Wire Stretcher, of which the following is a specification.

My invention relates to improvements in devices for stretching and repairing wire on fences.

10 The objects of my improvements are, first, to provide means for forming the particular wire-splice described below, entitled "Plate-link splice," and for utilizing the plate-link thereof to form a simple substitute for one of 15 the two usual wire-grips; second, to provide as an auxiliary to the stretcher a means of bringing the slack wire end within reach of the stretcher and a powerful frame on which the stretcher shall be completed without the 20 intervention of any dangerous rope or chain; third, to provide a check-pawl without springs, yet automatic and safe; fourth, to provide a safe wire-grip self-tightening and which does not kink or otherwise mutilate the wire. I 25 proceed to show by what mechanisms I attain these objects.

Figure 1 is a perspective view of the plate-link splice aforesaid completely formed. Fig. 2 is an elevation of the fundamental parts 30 of the wire-stretcher. Fig. 3 is a plan of the same. Fig. 4 shows how the slack wire end is brought within reach of the stretcher-frame. Fig. 5 shows one position of the pawl. Fig. 35 6 is a sectional elevation through line *a b*, Fig. 2.

Similar letters refer to similar parts throughout.

The following is a detailed description of the same.

40 I. The plate-link splice consists of a plate-link *L* with a hole for each wire end. One wire is squarely bent near its end, threaded through the link up to the bend, and the projection sharply bent down on the link in a forward direction. When the stretching has been effected, the other wire is squarely bent at a suitable point and secured to the link in a corresponding manner with the first wire, but from the opposite side of the link. The 45 claw *C* is a two-fingered claw, the fingers being separated by a slot wide enough to allow the fencing-wire to enter freely. When one end of the link *L* has been secured to one wire, the cavity of the claw receives that end

of the link, while the tip of the claw retains 55 the link in a position suitable for splicing.

II. The auxiliary chain *ch* is a light chain with links suitable to engage with the claw *C* in the manner shown in Fig. 4. At one end is a hook *h*, which can seize the plate-link *L* 60 by its hole.

III. The combined frame and rack *R* shown has preferably a *H*-section. (See Fig. 6.) The horizontal rib is provided with a stepped rack *R* for purposes of hauling and retaining. 65 The vertical rib carries the slider *S* (to which is attached the wire-grip *Gg*) and the follower *F*, (to which is attached the check-pawl *P*.) The claw *C* is shown as a part of the frame *R*, and the grip *Gg* as a part of the slider *S*; but 70 the reverse arrangement may be adopted, if desired. To the forward end of the slider *S* are pivoted the drag-links *dl*, by which the slider is hauled. The operating-lever *le*, Fig. 2, is pivoted to the drag-links *dl*, and is 75 provided at one end with a tooth or teeth capable of engaging with the rack-steps *R*. A hook *k* is attached to the slider *S* as a means of seizing the auxiliary chain *ch* for the purpose described below. 80

IV. The follower *F*, with check-pawl *P* attached, is drawn along by a trailing wire *t*, attached to the slider *S*. In Figs. 2 and 3 it is shown acting as a check to the slider *S*, the pawl *P* sitting firmly down into a rack-step. 85 When the slider is hauled forward a little, the follower *F* is tilted forward into the position shown in Fig. 5, the fit of the follower on the vertical rib of the frame *R* being slack enough to allow such tilting. The pawl *P* is then 90 clear of the rack-steps. Should the slider *S* rush back, it knocks the follower *F* over into a vertical position with the pawl *P* jammed down into a rack-step. Further, the slackness of fit aforesaid is not enough to make it possible to lift the pawl wholly out of a step by a clear vertical lift. Thus the follower check-pawl described above is a safety appliance. 95

V. The bottom jaw *G* of the wire-grip *Gg* is provided by forming a smooth groove *G* in the slider *S* in such a manner that the wire can lie straight and in line. The top jaw *g* of the wire-grip *Gg* is provided by forming in the slider *S* a four-sided recess *r*, in which a hard-steel sleeve *s* fits loosely. An ordinary screw-bolt *bo*, passing through the sleeve *s* in a direction across the line of wire, secures the 100 105

sleeve to the slider S by a nut *n*. The lower face of the sleeve *s* is an incline *g*, running downward and outward in a direction across the line of wire and has corrugations *g* running in the same direction, and the combination of recess *r*, sleeve *s*, bolt *bo*, and corrugated incline *g* is such that on screwing up the nut of the bolt the sleeve *s* is drawn into the recess *r*, the incline *g* pressing the wire down into the groove *G* and each corrugation scoring the wire to an extent that insures the initial frictional grip of the corrugated face *g* of the sleeve on the wire being greater than that of the smooth groove *G* on the wire.

15 The upper face *s* of the sleeve *s* fits closely to that of the recess *r*, both being inclined downward in such a direction that the pull of the wire, acting on the sleeve *s* through the aforesaid initial friction set up between them 20 by screwing up the nut of the bolt *bo*, draws the sleeve down the recess-incline, creating by this means an additional and automatic grip on the wire. The seating of the washer *w* should be cylindrical to allow this motion.

25 To illustrate the working of the stretcher, I will describe how a broken wire is spliced. One wire end is placed within the grip *Gg*, leaving a few inches of free wire, Fig. 4, and the initial grip is given by screwing up the 30 nut *n*, Fig. 6. The second wire end is then fitted with a plate-link *L*, (in the manner described above,) to which the hook *h* of the auxiliary chain *ch* is secured, Fig. 4. The operator next places the slider S at the commencing end of the rack R, as in Fig. 4, and, drawing the chain *ch* and rack R together by hand, drops link *l'* of the chain *ch* into the 35 claw C. By a reciprocating motion the lever *le* now engages successively with the rack-steps, hauling the slider S along the rack (the follower check-pawl FP automatically, step by step, backing up the slider) until the hook *k* seizes that chain-link *l'* which is being held and presented by the claw C. (See dotted 40 picture of slider in Fig. 4.) At this juncture the tension-circuit is complete without the rack R and the claw C. Hence now if the pawl P is kept clear of the rack-steps by tilting the follower F with the fingers the claw C, 45 with the rack R, may be drawn forward to seize a fresh link *l'* of the chain, (see dotted picture of claw C in Fig. 4,) and the hook *k* may be detached from the chain. This cycle of operations is repeated until the claw C reaches and retains the plate-link *L*, as in 50 Figs. 2, 3, when the auxiliary chain *ch* may be removed, the final and heaviest part of the

stretching being done on the frame R alone. The splice is then completed as described above.

60

In stretching new wire the stretcher may be used either (Case 1) between the stretch-posts or (Case 2) at a stretch-post. In Case 1 the process will be similar to that for splicing, except that that half of the wire which is seized by the grip *Gg* need not be cut off the coil until the exact length required has been ascertained. In Case 2 it will be necessary first to fasten to the post a short auxiliary wire provided at its free end with a plate-link. Then proceed as in Case 1, except that the wire attached to the coil may in this instance be secured direct to the post and the auxiliary wire removed.

65

70

75

What I claim as my invention, and desire to secure by Letters Patent, is—

1. In a wire-stretcher of the class described, the combination with a fingered claw, of a wire coupling having openings adjacent to its opposite ends for connection with one wire end and to be received and held by the said claw, and movable means for connection with the other wire end to bring the latter in a position for engagement with the said coupling.

80

2. In a wire-stretcher, in combination, a chain provided at one end with a hook, a claw detachably engaging with the chain at one of several suitable points along it, a wire-grip, means for drawing the claw with the chain toward the wire-grip, a hook mounted on the wire-grip, for holding the chain during the reverse movement of the claw, all substantially as set forth, and for the purpose specified.

85

3. In a wire-stretcher, in combination, a rack-frame, a slider moving smoothly on the rack-frame and carrying a wire-grip, a follower and pawl integrally connected and mounted on the rack-frame behind the slider and operated by the slider substantially in the manner described.

90

4. In a wire-stretcher a wire-grip comprising in combination a piece having a smooth groove and a recess whose upper face is inclined, a hard sleeve working in the recess and having its lower face a corrugated incline, a bolt threaded through the sleeve, and a nut, all operating substantially as set forth.
